UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION.

EDGING-MACHINE.

1,207,590.

Specification of Letters Patent.

Patented Dec. 5, 1916.

Application filed September 25, 1916. Serial No. 122,114.

To all whom it may concern:

Be it known that I, ALBERT E. MAYNARD, a citizen of the United States, residing at Southbridge, in the county of Worcester and State of Massachusetts, have invented certain new and useful Improvements in Edging-Machines, of which the following is a specification.

My invention relates to improvements in edging machines and has particular reference to an improved machine particularly adapted for use in finishing the edges of ophthalmic lenses.

The leading object of the present invention is the provision of novel and improved means for controlling the transverse movement of the grinding stone or tool relative to the lens or lenses being ground.

Further objects of the invention include the provision of improved means for adjusting the width of the zone of movement of the stone or grinding member, and of additional and improved means for adjusting and controlling the path traversed by reciprocations of the same amplitude, whereby either or both adjustments may readily be made to at all times control the exact position of the stone and portion or portions of the stone operating upon the lenses.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a side elevation of a machine equipped with my improvements. Fig. II represents an enlarged fragmentary perspective view illustrating my improvement. Fig. III represents a top plan view of the machine indicating the variation accomplished by one of my adjustments. Fig. IV represents an enlarged view largely in section illustrating certain details of construction of my device.

In the drawings, in which similar characters of reference are employed to denote corresponding parts throughout the several views, the numeral 1 designates the base or tub of the edging machine, having rising therefrom the side flanges 2 provided with

the bearings 3 serving to slidably and rotatably support the spindle or shaft 4 bearing the grind stone 5. Secured to the forward portion of the tub is a suitable lens holding and rotating mechanism 6 for securing in position and rotating against the stone the lenses 7, while disposed at the rear of the machine is a driven shaft 8 provided with the barrel cam 9, the foregoing parts being but briefly described inasmuch as their specific construction forms no essential part of my present invention.

As has been mentioned, the shaft 4 for the stone is both rotatable in its bearings and also longitudinally slidable therein, this sliding being effected by the shift lever 10 having at one end the yoke 11 pivotally secured to the collar 12, which is loosely mounted on the shaft and held from rotation thereon as by the fixed collar 13 or other suitable device. The opposite end of the lever 10 is provided with a roller 14 riding in the groove 15 of the barrel cam, the lever being intermediately pivotally supported so that movement imparted to the one end through engagement of the barrel cam and roller will rock the lever and thus cause its opposite end to suitably shift the shaft 4.

My present invention relates especially to the pivotal mounting or supporting of this lever, particular attention in this connection being invited to Figs. II and IV of the drawings.

Secured to the side of the tub 1 is the flange 16 having the outwardly projecting boss 17, in which is suitably secured as by threading, the stud 18, locked in position as by the nut 19, and having the reduced outer portion 20 joining the main portion at the shoulder 21. Encircling the reduced portion is the exteriorly threaded sleeve 22 having secured on its outer end the knurled operating portion 23 and locked against outward movement by the washer 24 secured to the end of the portion 20, as by the screw 25 and engaging a portion of the outer end of the sleeve.

It will thus be noted, and particularly understood by reference to Fig. IV that the exteriorly threaded sleeve 22 is rotatably mounted on the outer portion of the stud 18, but being held between the shoulder 21 and washer 24 is locked against any longitudinal sliding movement relative to the stud.

Threaded onto the sleeve is the sleeve portion 26 of the pivot bracket 27, the sleeve portion having an inwardly projecting hub like member provided with the key 28, preferably rigidly secured to the hub and sliding in the key-way 29 of the stud 18, the key thus locking the bracket against rotative movement relative to the stud, while permitting of its longitudinal sliding upon rotation of the threaded sleeve 22, a knurled lock nut 30 on the sleeve 22 being adapted to bear against the bracket sleeve 26 to lock the parts in desired adjusted position.

The bracket 27 is provided with the dovetail or under-cut groove 31 slidably receiving the slide block 32 having the socket or aperture 33 to receive the pivot pin 34 of the slide member 35.

The slide has rising therefrom the pair of arms 36, between which are located the nut 37 engaging the threaded bar 38 secured to the lugs 39 rising from the shift lever 10. It will thus be understood that by rotation of the nut 37 it will be caused to travel back and forth along the rod 38 and on account of its engagement between the arms 36 will carry with it the slide pivot pin 34 and pivot block 32, thus varying the point of pivotance about which the lever will swing. A scale 40 on the lever coöperating with a suitable indicator or the like 41 on the slide serves to indicate the adjustment. Similarly, a scale 42 carried by the lug 17 serves to coöperate with the indicator line or edge 43 on the bracket sleeve 26 to indicate the proper adjustment of the bracket.

From the foregoing description taken in connection with the accompanying drawings, the construction of my improvement should be readily understood, while its advantages should be best appreciated by reference to Fig. III. In Fig. III, I have indicated in dotted lines one shifting of the stone attained by adjustment of the bracket 27 through rotation of the sleeve 22. By reference to this it will be noted that if the pivot is left in the same position or unadjusted and the several parts of the machine held against rotation that turning of the sleeve 22 in the one direction shifts the bracket 27 toward the left in Fig. III bearing with it the pivot, and thus causing a shifting of the lever, stone shaft and stone to the position indicated by the dotted lines, it being understood that this lateral shifting of the pivot will cause all movement of the stone to be nearer one side of the machine than the other but will in no wise affect the amount of lateral shifting of the stone imparted to the stone through the lever 10 upon rotation of the barrel cam. On the other hand, when it is desired to give a greater or less throw to the stone this result 65 can be accomplished by shifting of the slide

35 forwardly or rearwardly, the greater the forward movement of the slide, the less the amplitude of reciprocations of the stone, while the greater its shifting toward the rear, the greater the amplitude of said reciprocations.

It will thus be seen that by combined lateral and forward and back adjustments of the pivot any desired amount of transverse movement may be imparted to the stone and the positions of the movement controlled so that the lenses may act from center to both edges of the stone when but a single lens is in the holder, or the parts may be adjusted to take care of the insertion of a number of lenses such as indicated by the dotted lines in Fig. III, so that the stone in its middle position will be central with the quantity of lenses and the movement controlled so that the lenses will travel just to the edges of the stone, or in any desired relation thereto at the will of the operator, the graduations on the scales 40 and 42 being if desired so figured that when the indicators are set at corresponding points the stone will be properly adjusted and have the proper movement to take care of the predetermined number of average thickness lenses indicated by the graduations or designations on the indicator.

It will further be noted that by proper use of my improved adjusting devices it is possible to cause the lens to engage with a selected portion only of the base of the stone, as when one portion of the stone is worn away more than the other to wear the stone down equally, also that it is possible to quickly and easily adjust the stone to maximum amount of travel, as when it is desired to true up the same.

I claim:

1. In an edging machine, the combination with a longitudinally shiftable stone shaft, of an intermediately pivoted lever having one end engaging the stone shaft and the other end engaging shifting mechanism, and means for laterally shifting the pivot of the lever.

2. In a lens edging machine, the combination with a longitudinally shiftable stone shaft, of a pivoted rock lever for shifting the shaft, and means for laterally and longitudinally shifting the pivot to vary the path and amount of movement of the lever and thus of the stone.

3. In a machine of the character described, the combination with a shiftable grind stone shaft, of a pivoted rock lever for shifting the shaft, a pivot for the lever shiftable longitudinally of the lever, and means for longitudinally shifting said pivot.

4. In a machine of the character described, the combination with a shiftable grind stone shaft, of a pivoted rock lever for shifting the shaft, a pivot for the lever 150

- shiftable longitudinally of the lever, means for longitudinally shifting said pivot, and means for indicating the amount of shift of the pivot. 50
5. In a machine of the character described, the combination with a support and a transversely shiftable grind stone mounted on the support, of a rock lever for shifting the stone, a pivot about which the lever rocks, and means for shifting the pivot in a path parallel to the axis of the stone shaft, substantially as and for the purpose described. 55
- 10 6. In a machine of the character described, the combination with a support and a transversely shiftable grind stone mounted on the support, of a rock lever for shifting the stone, a pivot about which the lever rocks, and means for shifting the pivot at right angles to the axis of the stone shaft, substantially as and for the purpose described. 60
- 15 7. In a machine of the character described, the combination with a support and a transversely shiftable grind stone mounted on the support, of a rock lever for shifting the stone, a pivot about which the lever rocks, means for shifting the pivot in a path parallel to the axis of the stone shaft, and 65
- 20 means for shifting the pivot at right angles to the axis of the stone shaft, substantially as and for the purpose described. 70
- 25 8. In a machine of the character described, including a supporting member, a stone shaft journaled on said member for rotation and reciprocation, and means for shifting the stone, including a shift lever having one end rotatably engaging the shaft, means for automatically shifting the 75
- 30 lever, and a variable pivot mounting for the lever, said mounting including a laterally adjustable bracket having a guide way extending longitudinally of the machine, a pivot slidable in the guide way, a slide se- 80
- 35 cured to the pivot and movable along the bracket, said slide having a portion em- 85
- 40
- 45
9. An edging machine, including a support or tub, a guide member projecting laterally from the tub, a bracket slidably mounted on the guide member, means for relatively shifting the bracket and guide member and for locking the parts in desired relatively adjusted position, a slide pivotally and slidably mounted on the bracket and movable at right angles to the direction of movement of the bracket, a shift lever 60
- 50 slidably mounted on the slide, means for securing the lever, and slide in desired relatively adjusted position, means for rocking the lever, a stone shaft mounted on the support and connections between the shaft and 65
- 55 lever for reciprocating the shaft upon rocking of the lever. 70
- 60 10. In a device of the character described, the combination with a slideable stone shaft and a lever for shifting the shaft, of a pivot 75
- 65 for the lever, a bracket engaging the pivot, means for laterally shifting the bracket and pivot to vary the movement of the lever and stone, and means for indicating the effect of shifting of the bracket. 75
- 70 11. In a machine of the character described, the combination with a shiftable stone shaft, of a cam member for automatically shifting the shaft, a lever operatively connecting the cam and shaft for actuating 80
- 75 the latter, a slide on the pivot having a pivot engaging a portion of the stone support, and means for shifting the slide along the lever to vary the pivot point of the lever, substantially as and for the purpose de- 85
- 80 scribed. 85
- 85 In testimony whereof I affix my signature in the presence of two witnesses.

ALBERT E. MAYNARD.
